UNITED STATES PATENT OFFICE

137,359

DESIGN FOR A VESTEE

Helene Pons, New York, N. Y.

Application January 1, 1944, Serial No. 112,150

Term of patent 3½ years

To all whom it may concern:

Be it known that I, Helene Pons, a citizen of the United States, residing at New York city, in the county and State of New York, have invented a new, original, and ornamental Design for a Vestee, of which the following is a specification; reference being had to the accompanying drawing, forming a part thereof.

Fig. 1 is a plan view of a vestee, showing my new design, and in flat open condition.

Fig. 2 is a front view thereof, as worn on the person.

Fig. 3 is a side view of the vestee as shown in Fig. 2.

Fig. 4 is a back view of the vestee shown in Fig. 2.

I claim:

The ornamental design for a vestee, substantially as shown.

HELENE PONS.
